(57) **CLAIM**

The ornamental design for a doll, as shown and described.

DESCRIPTION

FIG. 1 is a perspective view of a doll showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent to the shaded areas which contain additional broken line details depict the bounds of the claimed design, while all other broken lines are directed to environment. The broken lines form no part of the claimed design.

1 Claim, 5 Drawing Sheets
